MAGNETIC TIMING DEVICE

Franklin S. Malick, Monroeville, Pa., assignor to Allis-Chalmers Manufacturing Company, Milwaukee, Wis.

Filed May 19, 1958, Ser. No. 736,263

9 Claims. (Cl. 307—88)

This invention relates generally to timing devices and in particular to those timing devices utilizing a magnetic core to obtain a long time delay.

Magnetic amplifiers have long been used in application where a high degree of reliability is desired. The reliability of a magnetic amplifier stems largely from the fact that it has no moving parts. Where such an amplifier is embodied in a control circuit the overall reliability of the control circuit is greatly decreased by the inclusion of moving parts such as relays, switches, or similar devices. In the cases where a time delay is desired it has heretofore been necessary to use some sort of a timing relay. This invention overcomes the disadvantage of the timing relay by providing a completely static timing device which has an output suitable for direct utilization by a magnetic amplifier. This timer thereby avoids the necessity for contacts or other moving parts to convert the output of the timing device into an output compatible to the magnetic amplifier type device.

It is therefore an object of this invention to provide a new and improved timing device.

Another object of this invention is to provide a static timing device for use with a magnetic amplifier which eliminates the need for relay type devices.

It is another object of this invention to provide a control system in which the output may be delayed after the application of an input signal.

Other objects and advantages of this invention will become apparent from the following description taken in connection with the accompanying drawings, wherein are set forth by way of illustration and example certain embodiments of this invention.

In the drawings,

Fig. 1 is a schematic presentation of the basic elements of my invention;

Fig. 2 is a drawing of the hysteresis curve for the core of Fig. 1;

Fig. 3 is a graphical presentation of the output of the core shown in Fig. 1;

Fig. 4 is a schematic drawing of a control system embodying my invention; and

Fig. 5 is a schematic drawing of another control system embodying my invention.

The basic theory of the magnetic timer is best explained with reference to the circuit of Fig. 1. The core 6, shown schematically, has the hysteresis loop shown in Fig. 2. Any suitable direct current source applies a current i_b to winding N_p . Therefore, winding N_p has ampere turns equal to $N_p i_b$. A second suitable direct current source applies a signal i_p which causes the winding N_p to have ampere turns equal to $N_p i_p$.

Assuming first that only the current i_b is flowing, the flux of the magnetic core will be at the negative saturation value $-\phi_s$ as shown at point A of Fig. 2. Assume now that $N_p i_p$ is equal to twice the magnitude of $N_p i_b$ and opposite in sign. The flux in the core will change to the positive saturation value $+\phi_s$ in response to the new value of total excitation applied to the magnetic core.

This flux change is not instantaneous but occupies a period of time. During the time the flux is changing in the core from negative saturation to a positive saturation a voltage E_s will be induced in winding N_s . This induced voltage E_s will cause a current i_s to flow through the total secondary resistance R_s connected to the winding N_s . This relationship may be expressed mathematically.

$$10 (1) \quad E_s = N_s \frac{d\phi}{dt} = R_s i_s$$

During the time that the flux in the core is changing, the hysteresis loop requires that the total ampere turns on the core must equal N_t . Since there are only three sources of ampere turns i_b , i_p and i_s , and since i_b and i_p have been determined as constants by defining them to be current sources, i_s must adjust itself so that the following equation is satisfied during the time that the flux in the magnetic core is changing.

$$15 (2) \quad NI_t = N_s i_s + N_p i_b + N_p i_p$$

The magnitude and direction which $N_s i_s$ must have is shown in Fig. 2. If we assume vertical sides to the hysteresis loop then i_s will remain constant throughout the entire flux change from negative saturation to positive saturation.

Solving Equation 1 for the value of t

$$30 (3) \quad dt = \frac{N_s}{R_s i_s} d\phi$$

$$(4) \quad \int_0^t dt = \frac{N_s}{R_s i_s} \int_{-\phi_s}^{+\phi_s} d\phi$$

$$35 (5) \quad t = \frac{N_s}{R_s i_s} (\phi_s + \phi_s)$$

Thus, we find that the time required for the flux to change equals:

$$40 (6) \quad t = \frac{2N_s \phi_s}{R_s i_s}$$

The current i_s may be plotted against time as shown in Fig. 3. The graph represents that the current i_p was applied at the time $t=0$. When the flux reaches the positive saturation point it can no longer change so the voltage E_s and therefore also the current i_s decrease to zero. If the current i_p is removed, it is obvious that exactly the same relations hold but i_s is in a reverse direction as the flux returns to the starting point A shown in Fig. 2.

50 It will be recognized, of course, that winding N_p might be divided into two separate windings of turns. The current source i_b would then feed one winding and the current source i_p would feed another winding. This might be desirable in the case where it is desired to keep two 55 circuits electrically distinct to prevent interaction. In the drawing of Fig. 1, winding N_p is shown as one winding for the sake of simplicity only. The ratio of N_b to N_p is 1:2 where it is desirable that the return of the core to negative saturation be accomplished in the same time as the increase in flux to positive saturation.

60 The current supplied to winding N_p may easily be furnished from the output of a magnetic amplifier. Similarly, the output current of the timer may also be used in conjunction with the control winding of a magnetic amplifier. Thus, we have a timing device which is completely compatible to the output and the input of a magnetic amplifier and requires no conversion of either the input or output signal.

A typical circuit embodying the timer of this invention is shown in Fig. 4.

70 In this embodiment an alternating current source 1 is connected by means of a switch 2 through conductors

3 and 4 to a magnetic amplifier 5. The magnetic amplifier has reactance windings 10 and 11 and positive feedback windings 12 and 13 connecting alternating current source 1 to a load 14 through self-saturating rectifiers 15 and 16. The reactance windings 10 and 11 coact to conduct current on alternate cycles of the supply voltage. For example, during one half cycle the current will flow through reactance winding 10 and feedback winding 12 to the load 14 through rectifier 16. On the next half cycle, current will reverse its flow through the load and flow through the rectifier 15, the feedback winding 13 and reactance winding 11 back to the alternating current source 1 through conductor 3.

Also wound on the same cores as the reactance windings 10 and 11 are bias windings 20 and 21. Bias windings 20 and 21 are series connected to be energized by the direct current output of the full wave bridge rectifier 22 through inductor 23, resistor 24 and conductors 25 and 26. The bias windings tend to drive the core of the magnetic amplifier to saturation, thereby increasing the current through the reactance windings, as indicated by the arrows adjacent windings 20 and 21. Resistor 24, in series with these windings, limits the current flowing in the windings to a predetermined value. Inductor 23 in circuit with bridge rectifier 22 and bias windings 20 and 21 serves to filter out undesirable components providing a more nearly constant direct current.

The direct current output voltage of bridge rectifier 22 also energizes an input winding 30 on the magnetic timer core 31 through inductor 23 and resistor 32. This winding induces a flux in the magnetic core in a direction tending to drive the core to positive saturation. A reset winding 33 on the magnetic core 31 is connected to be energized by a signal derived from the output of the magnetic amplifier. This signal is picked off across the load 14 and converted to direct current by rectifier 34. Resistor 35 limits the current to a predetermined level. The polarity of the flux induced in the core by winding 33 is opposite that of winding 30 and tends therefore to drive the flux in the magnetic core to negative saturation. A current flows in winding 33 only when magnetic amplifier 5 is producing an output current through load 14. Since amplifier 5 is a snap acting amplifier due to the positive feedback windings 12 and 13, the resulting current in winding 33 will be largely a function of the size of resistor 35.

The magnetic memory core 31 has an output winding 40 which is connected to control windings 41 and 42 on the magnetic amplifier. Control windings 41 and 42 are polarized so as to decrease the output of magnetic amplifier 5, as indicated by the arrows adjacent these windings. The magnitude of the current flowing in control windings 41 and 42 is sufficient to overcome the ampere turns of the bias winding and maintain the desaturation of the magnetic amplifier. As mentioned earlier, the magnitude of the current in windings 40, 41 and 42 is determined by the rate of change of flux in core 31. This cuts off magnetic amplifier 5 and prevents an output current from flowing in reactance windings 10 and 11.

A typical operation of this circuit would be as follows. Magnetic core 31 is necessarily at negative saturation prior to the beginning of a cycle for reasons to be explained later. When switch 2 is closed, power will be applied to rectifier bridge 22 from alternating current source 1. The direct current output of bridge 22 will flow through inductor 23, the resistor 32 and winding 30 on the magnetic core 31. The current flowing through winding 30 immediately starts to drive the magnetic core toward positive saturation. The resultant changing flux in the magnetic core 31 induces a current in winding 40 which is connected in series with control windings 41 and 42 on magnetic amplifier 5. The ampere turns of control windings 41 and 42 induce a flux in the core of magnetic amplifier 5 which drives the magnetic amplifier to cut off so that no output is produced. The magnitude

of this current in control windings 41 and 42 is determined by the rate of change of flux in core 31 and is sufficient to prevent any output from the magnetic amplifier. In other words, there is no current flowing in the reactance windings and the entire supply voltage is absorbed by the magnetic amplifier.

Bias windings 20 and 21 are connected through resistor 24 to be energized by the direct current output of the bridge rectifier 22. Windings 20 and 21 tend to drive the magnetic amplifier to full output by saturating the core of magnetic amplifier 5. The ampere turns of the bias windings 20 and 21, however, are not sufficient to overcome the ampere turns of the control windings 41 and 42 and therefore the magnetic amplifier remains cut off. When the winding 30 has driven the core 31 to positive saturation the flux ceases to change and the voltage induced across winding 40 drops to zero.

This means that there will be no current flowing in control windings 41 and 42. The ampere turns of the bias winding therefore will tend to drive the magnetic amplifier to full output.

As soon as current starts to flow in the reactance windings 10 and 11 the positive feedback windings 12 and 13 take over and quickly increase saturation of the core until the magnetic amplifier is delivering full output to the load 14. The magnetic amplifier will remain at full output until the switch 2 is opened.

As soon as an output current flows through the load 14, the voltage developed across the load energizes a reset winding 33 on memory core 31 which drives the core to negative saturation once again. This, of course, induces a current in winding 40 connected to control windings 41 and 42 however, the ampere turns of control windings 41 and 42 are not sufficient to overcome the sum total ampere turns of both the bias windings 20 and 21 and the feedback windings 12 and 13. The time required to reset the magnetic core is governed by the size of the resistor in series with the winding and the voltage induced across the load of the magnetic amplifier.

When the switch is opened, the exciting current to magnetic amplifier 5 is removed and the load is thereby deenergized. Reclosing the switch initiates another timing cycle since the core is at negative saturation.

It will be obvious that the load 14 of the magnetic amplifier 5 can be the control winding on another magnetic amplifier, a relay winding, motor or other similar load. The drawing illustrates the use of a winding of a relay 44 as the load 14.

Fig. 5 shows a control circuit that is generally similar to the circuit of Fig. 4 except that the circuit of the reset winding 33 is isolated from the circuit of the magnetic amplifier 5 and the load 14 that is controlled by the magnetic amplifier. The reset winding 33 is connected to the direct current terminals of the bridge rectifier 22 through a resistor 35 and the contacts 45 of the relay 44. When the winding 14 of the relay 44 is energized by the magnetic amplifier 45, the contacts 45 close and the core 31 is driven to reverse saturation by current from the bridge rectifier 22. When the magnetic amplifier is deenergized by opening the switch 2, the contacts 45 of the relay open to interrupt the current to the reset winding 33.

What is claimed is:

1. In a control system, a static timing device comprising a saturable magnetic core, input winding means on said core, amplifier means having an input and an output; an output winding on said core for developing a voltage responsive to a changing flux in said core, a source of direct current, means for supplying said input winding means with a direct current from said source to drive said core to magnetic saturation, said output winding being coupled to said amplifier input to form a circuit for carrying current in said output winding in response to the current in said input winding and according to the time elapsed while said input winding is supplied with

direct current, and means responsive to the output of said amplifier to energize said input winding means and reverse the saturation of said core.

2. In a control system, a static timing device comprising a saturable magnetic core, an input winding on said core, an output winding on said core for developing a voltage responsive to a changing flux in said core, a source of direct current, means for supplying said input winding with a direct current from said first source to drive said core to magnetic saturation, amplifier means responsive to the voltage induced across said output winding by the changing flux in said core, a reset winding on said core, means responsive to the output of said amplifier to energize said reset winding to reverse the saturation of said core.

3. In a control system, a static timing device comprising a saturable magnetic core, an input winding on said core, an amplifier having an input and an output, an output winding on said core for developing a voltage responsive to a changing flux in said core, a source of direct current, means for supplying said input winding with a direct current from said source to drive said core to magnetic saturation, said output winding being coupled to said amplifier input to form a circuit for carrying current in said output winding in response to the current in said input winding and according to the time elapsed while said input winding is supplied with direct current, and means responsive to the output of said amplifier to reverse the magnetomotive force of said input winding thereby driving said core to reverse saturation.

4. In a control system, a static timing device comprising a saturable magnetic core, input winding means on said core, an output winding on said core for developing a voltage responsive to a changing flux in said core, a first source of direct current, means for supplying said input winding means with a direct current from said first source to drive said core to magnetic saturation, amplifier means responsive to the voltage induced across said output winding by the changing flux in said core, a second source of direct current, means responsive to the output of said amplifier to energize said input winding means from said second source to reverse the saturation of said core.

5. In a control system, a static timing device comprising a saturable magnetic core, an input winding on said core, an output winding on said core for developing a voltage responsive to a changing flux in said core, a reset winding on said core, a source of direct current, means for supplying said input winding with a direct current from said source to drive said core to saturation, a magnetic amplifier having a bias winding, a control winding and reactance windings, means for energizing said bias winding from a direct current source to increase the output of said amplifier, means connecting said control winding to be energized by the voltage developed across said output winding to reduce the output of said amplifier, means connected to said reactance windings and said reset winding to reverse the saturation of said core in response to an output current through said reactance windings.

6. In a control system, a static timing device comprising a saturable magnetic core, an input winding on said core, an output winding on said core for developing a voltage responsive to a changing flux in said core, a reset winding on said core, a source of direct current, means for supplying said input winding with a direct current from said source to drive said core to saturation, a mag-

netic amplifier having a control winding, a bias winding, a feedback winding, and reactance windings, means for energizing said bias winding from a direct current source to increase the output of said amplifier, means connecting said control winding to be energized by the voltage developed across said output winding to reduce the output of said amplifier, means connecting said feedback winding to be energized by the output of said magnetic amplifier to further increase the output of said amplifier, means isolating from said magnetic amplifier to energize said reset winding and reverse the saturation of said core in response to the output of said amplifier.

7. In a control system, a static timing device comprising a saturable magnetic core, an input winding on said core, an output winding on said core for developing a voltage responsive to a changing flux in said core, a reset winding on said core, a source of direct current, means for supplying said input winding with a direct current from said source to drive said core to saturation, a magnetic amplifier having a control winding, a bias winding, a feedback winding and reactance windings, means for energizing said bias windings from a direct current source to increase the output of said amplifier, means connecting said control winding to be energized by the voltage developed across said output winding to reduce the output of said amplifier, means connecting said feedback winding to be energized by the output of said magnetic amplifier to further increase the output of said amplifier, means responsive to the output of said magnetic amplifier to energize said reset winding to reverse the saturation of said core.

8. In a control system, a static timing device comprising a saturable magnetic core, an input winding on said core, an output winding on said core for developing a voltage responsive to a changing flux in said core, a reset winding on said core, a source of direct current, means for supplying said input winding with a direct current from said source to drive said core to saturation, a magnetic amplifier having a control winding, a bias winding, a feedback winding and reactance windings, means for energizing said bias windings from a direct current source to increase the output of said amplifier, means connecting said control winding to be energized by the voltage developed across said output winding to reduce the output of said amplifier, means connecting said feedback winding to be energized by the output of said magnetic amplifier to further increase the output of said amplifier, means responsive to the output of said magnetic amplifier to energize said reset winding to reverse the saturation of said core.

9. In a control system, a static timing device comprising a saturable magnetic core, an input winding on said core, a source of direct current, means for supplying said input winding with a direct current from said source to drive said core to magnetic saturation, an output winding on said core for developing a current in response to a changing flux in said core, a current responsive amplifier connected to said output winding, a reset winding on said core means responsive to the output of said amplifier to energize said reset winding and reverse the saturation of said core.
